UNITED STATES PATENT OFFICE.

WILLIAM T. BRADLEY, OF ROCHESTER, NEW YORK, ASSIGNOR OF ONE-HALF TO LOUIS P. WILLSEA, OF SAME PLACE.

WRINGER.

SPECIFICATION forming part of Letters Patent No. 640,441, dated January 2, 1900.

Application filed October 3, 1898. Serial No. 692,498. (No model.)

To all whom it may concern:

Be it known that I, WILLIAM T. BRADLEY, of Rochester, in the county of Monroe and State of New York, have invented certain new and useful Improvements in Wringers; and I do hereby declare the following to be a full, clear, and exact description of the same, reference being had to the accompanying drawings, forming a part of this specification, and to the reference-numerals marked thereon.

My present invention has for its objects to improve the construction and operation of clothes-wringers, particularly that class in which the pressure between the rollers is caused by spring action; and to these ends it consists in certain improvements in construction and combinations of parts, all as will be hereinafter described and the novel features pointed out particularly in the claims at the end of this specification.

In the drawings, Figure 1 is a perspective view of a wringer constructed in accordance with my invention; Fig. 2, a vertical sectional view of the same; Fig. 3, a sectional view on the line *x x* of Fig. 2; Fig. 4, a view showing one of the guard-plates.

Similar reference-numerals indicate similar parts.

The main frame of the wringer embodies two side members or brackets 1, containing the bearings for the rollers and connected by the plate or web 2, which latter is engaged between the ribs 3 on the members 1 and secured by the screws 4 passing through said plate and also through perforated lugs 5 on the members and serving as the pivots of the swinging clamping-arms 6. The arms 6 are provided with clamping-screws 7, which operate with the downward extensions 8 on the side frames or members to clamp and hold the machine upon a tub or other suitable support, and the independent swinging motion of the clamps enables the machine to be attached to tubs having various diameters.

The rollers employed are of the usual construction, being covered with rubber, and when in use their surfaces are in contact, their arbors 9 resting in half bearing-blocks 10 and 11, preferably of wood, and as each of the side frames or members is open at the front the rollers may be inserted and removed

without separating said frames. The bearing-blocks 10 for the lower roller are arranged in recesses or sockets formed in the body of the members 1, and the blocks 11 of the upper roller are arranged in sockets in the ends of journal-boxes 12, having cylindrical extensions 13 operating in recesses 14, formed in the members 1 directly over the lower blocks 10.

15 indicates springs arranged in the recesses 14 and operating to press the boxes down and to hold the rollers in contact, the approach of said rollers being limited by adjusting rods or screws 16, passing loosely through the frame and preferably screwing into the tops of the boxes, so that by drawing the boxes upward against the tension of the springs the machine may be arranged for operating on heavy goods, or the rollers may be kept in very light contact, just sufficient to hold them in place when not in use. The rods or screws 16 may be rotated for the purpose of adjusting the rollers by the springs; but I prefer to secure a more rapid adjustment by a cam action, and for this reason provide the screws with enlarged heads 30, fitting in recesses in the ends of levers 31 and having the transverse pins 32 extending through cam-slots 33, formed in the sides of 80 said levers, as shown. The cam-slots are so arranged relative to the handles or operating ends of the levers that when the latter are in the position shown in full lines in the drawings the rollers are in contact under spring-pressure; but when the levers are raised the screws are moved upward and the pressure is entirely removed from the rollers. This arrangement not only facilitates the construction of the parts, but a rapid adjustment may be had by moving the cam-levers, or the screws 85 may be rotated in the boxes, the lower surface of the levers then resting on the top of the frame 1. If desired, the screws 16 could be made rigid relative to the boxes or bearings 12 and the cams alone employed to adjust the latter.

17 indicates guard-plates arranged at the ends of the rollers to prevent the contact of the goods with the frame, said plates having apertures 18 for the passage of the arbors of the rollers and the inwardly-turned flanges

19. One of the apertures 18 in each guard-plate is elongated somewhat to permit of the relative adjustment of the rollers, and when in position the outer sides of the plates are 5 against the journal-boxes of the upper roller to prevent longitudinal movement of the rollers.

The parts of the machine-frame are very few and simple, only two bolts being required to fasten the parts together, and all said parts 10 are castings which can be easily and cheaply made. Furthermore, the rollers can be easily removed and inserted when desired by moving the upper half-bearings vertically by the 15 adjusting-screws until the journals of the upper roller are released and then withdrawing the rollers through the open fronts of the main frame.

I claim as my invention—

1. In a wringer, the combination with the 20 main frame composed of the side frames having the bearings thereon, the flanges and lugs, the connecting web or plate extending between the frames and engaging the flanges, and the bolts passing through the lugs and 25 plate, of the clamp-arms pivoted on the bolts, and the rollers journaled in the bearings in the frames.

2. In a wringer, the combination with the main frame embodying the side members, 30 each open at the front and having the stationary bearings and the recesses above them, of the movable journal-boxes, the separate springs located in the recesses and engaging the movable journal-boxes, the rods engaging 35 the movable journal-boxes and extending through the upper portion of the frame, adjustable means operable from the upper portion of the frame for limiting the movement of the boxes caused by the springs, and the 40 rollers.

3. In a wringer, the combination with the main frame embodying the side members open at the front, having the downward extensions, and the stationary bearings, the connecting- 45 web, and the bolts connecting the members and web, of the clamp-arms pivoted on the bolts, the movable journal-boxes, the springs for operating them, adjusting devices for limiting the movement of the boxes, and the 50 rollers.

4. In a wringer, the combination with the

main frame embodying the side members open at the front, having the sockets, the stationary bearing-blocks therein, and the recesses over them, of the movable journal-boxes 55 guided to move in the recesses, the springs arranged in said recesses, the screws engaging the boxes, and the rollers.

5. In a wringer, the combination with the main frame embodying the side members open 60 at the front, and having the recesses 14, and the stationary bearings beneath, of the journal-boxes 12 having the extensions operating in the recesses 14, the springs in said recesses, means for adjusting the journal-boxes independently against the tension of the springs, and the rollers.

6. In a wringer, the combination with the main frame embodying the side members open 70 at the front, and having the recesses 14, and the sockets beneath, and the removable bearing-blocks therein, of the journal-boxes 12 having the extensions operating in the recesses 14, and the bearing-blocks 11 therein, the springs, means for adjusting the journal-boxes 75 independently against the tension of the springs, and the rollers.

7. In a wringer, the combination with the main frame, the stationary roller, the adjustable roller, and the journal-boxes for the latter, of the rods connected to said boxes having the pins, and the levers having the cam-slots in which said pins operate.

8. In a wringer, the combination with the main frame, the stationary roller, the adjustable roller, and the journal-boxes for the latter, of the threaded rods screwing into the boxes, and the cam-levers connected to the upper ends of the rods and engaging the 85 frame.

9. In a wringer, the combination with the main frame, the stationary roller, the adjustable roller, and the journal-boxes for the latter, of the threaded rods screwing into the boxes, having the heads and the pins thereon, and the levers having the cam-slots 95 engaging the pins, and also engaging the main frame.

WILLIAM T. BRADLEY.
